UNITED STATES PATENT OFFICE.

HENRY M. NICHOLLS, OF MAYWOOD, ILLINOIS, ASSIGNOR TO AMERICAN CAN COMPANY, OF NEW YORK, N. Y., A CORPORATION OF NEW JERSEY.

POURING SPOUT FOR CONTAINERS.

Application filed March 28, 1925. Serial No. 17,517.

My present invention relates to pouring spouts for containers and particularly to spouts of the attachable type adapted to be applied to the nozzle of an already formed container. While the invention may be used upon containers of various kinds, the particular and important use contemplated is upon cans of the large square or round type commonly used by distributors of oil and similar commodities.

In the manufacture of oil cans of this type, it is very desirable that the can maker should be enabled to carry a standard stock of cans equipped with pouring nozzles, but without spouts, since some distributors require spouts on their cans, while others do not desire them. With the cans thus formed, the manufacturer may supply both demands from his regular stock, the pouring spouts, when constructed in accordance with my invention, being readily attachable to the completed containers when they are desired.

An important object of the invention is the provision of an attachable pouring spout arrangeable upon the nozzle in such manner as to cause it to remain relatively rigid, both when in pouring position, extended over the edge or rim of the container, and in the inoperative position, turned inwardly from the periphery of the can, and this even though the spout is disposed in different planes in the two positions.

Another object is the provision of a spout which may be quickly and easily applied to a nozzle having an enlarged top portion, or to a nozzle of tapered form, the spout for this purpose having a yieldable flange, or wall, surrounding the opening through which the nozzle extends, so that the spout may be applied by pressing it downwardly over said nozzle.

Another feature of the invention is that the spout is so formed as to provide a serrated wall or flange part adapted to engage the nozzle and to provide frictional resistance tending to hold the spout in the position in which it is arranged.

Another feature of advantage of my improved spout is that after it has been positioned it is impossible to remove it without permanent mutilation, which will prevent its use upon other cans, this being of considerable importance in view of a commonly experienced difficulty in the past of having

attachable spouts removed from the cans upon which they have been applied and appropriated for other purposes.

It is contemplated that the spout, when arranged in inoperative position, may be substantially beneath the top edge of the container, so that containers equipped with the spouts may be stacked end upon end for transportation and storage.

Numerous other objects and advantages of the invention will be apparent as it is better understood from the following description, which, taken in connection with the accompanying drawings, discloses a preferred embodiment thereof.

Referring to the drawings,

Figure 1 is a perspective view of a pouring spout embodying my invention;

Fig. 2 is a partial cross section of the top of a nozzle can equipped with said spout; and

Fig. 3 is a top plan view of a portion of the container showing the spout in the inoperative position.

On said drawings, illustrating the best manner in which I have thus far contemplated applying the principles of my invention, the reference character 11 indicates the body of a container having an end member 12 secured thereto at the top by means of a double seam 13, or in any suitable manner, said end member having, in the present instance, a circumferential channel 14 in the outer part thereof, said channel being widened at one side of the end to provide a depression 15 in which the nozzle 16 is disposed. Said nozzle, in the present instance, is secured to the end by means of an upstanding flange 17 disposed in a necked-in portion 18 of the nozzle, the inner end of the nozzle being flanged outwardly on the under side of the end member, as indicated at 19, and a gasket 21 being interposed between the flange and said end. The top of the nozzle is enlarged, as shown at 22, and is adapted to be closed by a cap (not shown), of any suitable form.

The spout, shown in detail in Fig. 1, comprises a sheet metal member having a flanged lip 23, providing a passage through which the material is adapted to be poured, and a circular attaching portion 24 rearwardly thereof, said portion having an opening 25 therein and an upwardly curved wall or flange 26 surrounding said opening. Said flange or wall is formed with a plurality of

radial slits 27 therein, extending about the sides and the rear of the opening, the forward part of the wall being solid and a depression 28 being formed at the base thereof. The spout is adapted to be applied by arranging it over the nozzle 16 and pressing it downwardly so that lips 29, provided by the slits in the wall 26 will yield outwardly, enlarging the opening sufficiently to permit the upper enlarged end 22 of the nozzle to 10 pass therethrough, said lips then tightly engaging the nozzle beneath said enlarged portion thereof, whereby the spout is held firmly in place, either in inoperative position, as shown in Fig. 3, or in pouring position, as shown in Fig. 2. In this position the outer end of the spout is somewhat forced up by the top of the seam 13, the lips 29 yielding for the purpose and also 15 causing the spout to be depressed or to spring down into its recess 15 when it is turned inward as in Fig. 3. The rear edge of said spout is beaded, as shown at 31, and adapted to engage the depressed portion 15 20 of the end 12 and it will be understood that the lip portion 23 of the spout when depressed in inoperative position as seen in Figure 3, is in substantially the plane of the end member, as is clearly indicated in said 25 figure wherein is shown by dotted lines the depression 14, 15, in which the lip and depressed portion 28 of the spout may rest, it being, however, raised from said plane when turned to pouring position, extending over 30 the edge or rim of the container. Considerable difficulty has been experienced in the past in providing a spout which would be firmly held upon the nozzle in either of these two positions, and I not only accomplish 35 this, but provide for holding the spout in adjusted position, the space between the lips 29 of the wall 26 producing a serrated edge, affording considerable frictional resistance 40 to turning of the spout. It will be noted 45 that when the spout is in the position shown in Fig. 3, it is disposed substantially below the top of the rim provided by the seam 13 and the cans may, therefore, be stacked 50 end upon end for convenience in packing. 55 The upward inclination of the wall 26 renders it very difficult, or impossible, to remove the spout after it has once been positioned without permanent mutilation thereof and it, therefore, cannot be appropriated for use upon other containers, as has been 60 possible with many of the spouts used in the past. It is thought that the invention and many 65 of its attendant advantages will be understood from the foregoing description, and it will be apparent that various changes may be made in the form, construction and arrangement of the parts without departing from the spirit and scope of the invention, 70 or sacrificing all of its material advantages,

the form hereinbefore described being merely a preferred embodiment thereof.

I claim:

1. A pouring spout for nozzle type containers, comprising a member arrangeable upon the nozzle after the latter is applied to the container, said member having a pouring channel therein and having an opening through which the nozzle may extend, said opening being normally of less diameter than the top of the nozzle and being surrounded by an outwardly yieldable resilient wall, whereby the spout may be positioned by pressing the same downwardly over the nozzle. 80

2. A pouring spout for nozzle type containers, comprising a member arrangeable upon the nozzle after the latter is applied to the container, said member having a pouring channel therein and having an opening through which the nozzle may extend, said opening being normally of less diameter than the top of the nozzle and being surrounded by an outwardly yieldable resilient wall, whereby the spout may be positioned 85 by pressing the same downwardly over the nozzle, said resilient wall being adapted to tightly grip the nozzle after the spout is positioned to hold the latter in rigid relationship. 90 95

3. A pouring spout for nozzle type containers, comprising a member arrangeable upon the nozzle after the latter is applied to the container, said member having a pouring channel therein and having an opening through which the nozzle may extend, said opening being normally of less diameter than the top of the nozzle and being surrounded by an outwardly yieldable resilient wall, whereby the spout may be positioned 100 by pressing the same downwardly over the nozzle, said resilient wall being adapted to tightly grip the nozzle after the spout is positioned to hold the latter in rigid relationship and the spout being rotatable upon 105 the nozzle from inoperative position within the periphery of the container to pouring position extending over the edge of said container. 110

4. A pouring spout for nozzle type containers, comprising a member arrangeable upon the nozzle after the latter is applied to the container, said member having a pouring channel therein and having an opening through which the nozzle may extend, said opening being normally of less diameter than the top of the nozzle and being surrounded by an outwardly yieldable resilient wall, whereby the spout may be positioned 115 by pressing the same downwardly over the nozzle, said resilient wall being adapted to tightly grip the nozzle after the spout is positioned to hold the latter in rigid relationship and the spout being rotatable upon 120 the nozzle from inoperative position within 125 the periphery of the container to pouring position extending over the edge of said container. 130

the periphery and beneath the top edge of the container to pouring position extending over the edge of said container.

5. A pouring spout for nozzle type containers, comprising a member arrangeable upon the nozzle after the latter is applied to the container, said member having a pouring channel therein and having an opening through which the nozzle may extend, said 10 opening being normally of less diameter than the top of the nozzle and being surrounded by a resilient wall having a plurality of radial slits therein rendering the same outwardly yieldable under pressure, 15 whereby the spout may be positioned by pressing the same downwardly over the nozzle.

6. A pouring spout for nozzle type containers, comprising a member having an 20 opening therein surrounded by an outwardly yieldable wall arrangeable in gripping relation upon the nozzle by downward pressure on the spout, forcing said nozzle through said opening.

25 7. A pouring spout for nozzle type containers, comprising a member having an opening therein surrounded by an outwardly yieldable wall arrangeable in gripping relation upon the nozzle by downward pressure on the spout, forcing said nozzle through 30 said opening, said wall having serrations therein adapted to hold the spout in adjusted position upon the nozzle.

35 8. A pouring spout for nozzle type containers, comprising a member having an opening therein surrounded by an outwardly

yieldable wall arrangeable upon a nozzle having an enlarged upper part by downward pressure on the spout, forcing the enlarged part of said nozzle through said opening, said wall thereafter engaging the nozzle with a gripping action beneath said enlarged part thereof. 40

9. A pouring spout for nozzle type containers, comprising a member arrangeable 45 upon the nozzle and being rotatable thereon from inoperative position within the periphery of the can to pouring position extending over the can edge or seam, said member having a flange adapted to rest upon the top 50 of the can and to hold the spout tightly in contact with the seam when in pouring position.

10. A pouring spout for nozzle type containers, comprising a member arrangeable 55 upon the nozzle after the latter is applied to the container, said member having a pouring channel therein and having an opening through which the nozzle may extend, said opening being surrounded by a resilient wall 60 having a plurality of radial slits therein rendering the same outwardly yieldable under pressure, whereby the spout may be positioned by pressing the same downwardly 65 over the nozzle, and whereby the spout may be rotatably lifted from inoperative horizontal position within a recess which surrounds said nozzle and caused to ride on the top edge of the container and held tightly in inclined pouring position.

HENRY M. NICHOLLS.
